MOTORCYCLE WHEEL MOUNT

John E. Kennedy, 6122 Anthony Ave.,
Garden Grove, Calif. 92641

Filed Dec. 27, 1971, Ser. No. 212,887

Term of patent 14 years

Int. Cl. D12—11

U.S. Cl. D12—118

FIG. 1 is a side elevational view of a motorcycle wheel mount showing my new design;

FIG. 2 is a front elevational view thereof;

FIG. 3 is a rear elevational view thereof;

FIG. 4 is a top plan view thereof; and

FIG. 5 is a bottom plan view thereof.

I claim:

The ornamental design for a motorcycle wheel mount, substantially as shown.
